RETRACTABLE LANDING LIGHT

Lester F. Lemm, Lynwood, Calif., assignor to Fred
G. Breding, Huntington Park, Calif.

Application October 30, 1933, Serial No. 695,861

7 Claims. (Cl. 240—7.7)

My invention relates to a pivoted type of landing light for airplanes in which the light or lamp housing when in its inoperative position is housed in the structure of the airplane, such as 5 being housed in the wing or in the fuselage or other suitable place, this being in order that there will not be an air resistance or disturbance to the air flow created by any projecting parts of the landing light. The pivoted landing lights, 10 for instance, are illustrated in the patent to Van Horn, 1,793,656, of February 24, 1931, for airplane landing light.

An object and feature of my invention in connection with the pivoting landing light is a simplified and strong construction for swinging the light on a pivot in order to house the light or to project or extend the light for illumination purposes.

A further detailed feature is the provision of 20 a type of rotating or oscillating device by which the light may be extended or projected from the wing or body of the airplane and held at any desired angle of inclination against the reaction of the air while the airplane is in flight. For this 25 purpose I mount the light on a substantial arm structure which is secured to an oscillating shaft and this shaft is oscillated by means of a worm and worm gear drive, the worm being rotated by a drum or sheave having a cable leading to 30 suitable controls operated by the pilot.

A further detailed feature of my improvement relates to the structure of the arm. This is made in a plurality of parts, one of which is in the 35 form of a bracket structure which oscillates with the main oscillating shaft and the other a projecting arm to which the lamp housing and the reflector are attached. This structure in its articulate movement moves the lamp from its housed 40 position to a projected or extended position in which a movement up to or somewhat greater than 90 degrees may be obtained. The lamp and the projecting part of the arm extends through an opening in the wing or the airplane body structure. The lamp when projected may be 45 held at any desired angle in reference to the body surface in which it is housed and, therefore, if located in the lower part of the wing it may have any desired inclination as to the longitudinal, horizontal axis of the airplane when this is presumed to be flying in a horizontal plane. When the lamp is housed in the wing the arm oscillates in a vertical plane. Or if the lamp is housed in the fuselage, for instance, the nose of 50 the airplane, and the projecting arm swings in

a horizontal plane, the lamp may have any desired inclination to project the light straight ahead, across the nose of the airplane or project the light outwardly, this being in a horizontal plane if the airplane is flying horizontally.

Another object and feature of my invention is a tilting or inclining mechanism for the lamp so that this may be oscillated on the axis of the projecting arm and, therefore, should the arm operate in a vertical plane, as when the lamp is housed in the lower surface of the wing, the lamp may oscillate on opposite sides of the vertical plane of the projecting and retracting movement of the lamp. Or if the lamp is housed in the nose of the fuselage or other place in the fuselage and is swung in a horizontal plane the inclining or tilting movement will tilt the beam of light either upwardly or downwardly in reference to this horizontal plane.

An object and feature of my invention in regard 20 to the tilting or inclining movements of the lamp comprise partly rotating the extension arm which carries the lamp on its axis and in my construction this is done by using an oscillating arm connected to the extension arm and shifting the oscillating arm by means of a reciprocating rod operating in alignment with the main oscillating or rotating shaft. This is, in my construction, performed by means of a worm drive gear operating 25 on a screw on the reciprocating rod.

Another feature of my invention relates to 30 transmitting the movement from the reciprocating rod to the oscillating arm by a resilient construction, such as by springs, so that when a certain 35 inclination or tilt is obtained the worm and its rotating drum or sheave may be left in a fixed position and the lamp when housed brought to its neutral or inoperative position flush with the surface of the wing or the fuselage in which the lamp is housed.

A further object and feature of my invention is 40 a construction for automatically bringing the tilted or inclined lamp housing to its neutral or inoperative housing position and this, in my invention, uses tracks which engage a roller on the end of the oscillating arm and brings this arm into a central position when the lamp is housed. Therefore, when the lamp is again projected by the swinging movement of the extension arm the 45 springs will automatically swing the lamp to its tilted or inclined position.

My invention is illustrated in the accompanying drawings, in which:

Fig. 1 is a plan of my invention taken in the di- 55

rection of the arrow 1, presuming the lamp to be in its housed position in the lower surface of a wing.

Fig. 2 is a longitudinal section on the line 2—2 5 of Fig. 1 in the direction of the arrows, the extension arm and lamp housing being shown in elevation with the lamp in the housed position.

Fig. 3 is a section similar to Fig. 2 with the lamp projected.

10 Fig. 4 is a section on the line 4—4 of Fig. 3, taken in the direction of the arrows, showing in dotted lines the tilted or inclined positions of the lamp.

Fig. 5 is an enlarged transverse section on the line 5—5 of Fig. 1 in the direction of the arrows.

15 Fig. 6 is a longitudinal section on the line 6—6 of Fig. 5 in the direction of the arrows through the worm drive for inclining or tilting the lamp housing.

Fig. 7 is a longitudinal section on the line 7—7 20 of Fig. 5 in the direction of the arrows, showing the worm and worm wheel drive for projecting and retracting the lamp from its housed position in the wing or airplane body.

Fig. 8 is a perspective view of part of an airplane illustrating the fuselage and the wings.

Referring first to the details in Figs. 1, 2, 3, and 5, the covering structure of an airplane wing or body, such as the nose of the fuselage, is indicated by the numeral 11. This may be a fabric 30 or metal covering or other suitable material and this material is provided with a circular opening 12 or an opening of any outline to accommodate the particular shape of the lamp. A metal or other suitable protecting ring 13 is secured to the 35 outer surface of the wing or body structure, forming a protective element. At the side of the surface covering of the wing or fuselage there is a base plate 14 and this is mounted and supported by any suitable structure, the details not being 40 illustrated herein as this will differ in accordance with the manner of constructing the airplane wings or the fuselage.

The lamp, designated by the assembly numeral 15, has a suitable reflector 16 with a flange structure 17, the flange engaging with the ring 13 and on the inside thereof when the lamp is housed as illustrated in Fig. 2. The glass or lens of the lamp is indicated at 18. A hub structure 19 is connected to the inner portion of the lamp housing or reflector and to this is secured a circular clamp 20 having fastening screws 21 on one side and a flange 22 with fastening screws 23 on the opposite side. The clamp portion 24 is thus secured to an extension arm 25 of the arm 55 assembly 26.

This arm assembly has an elongated bearing hub 27, through which extends the extension arm 25, and formed rigid with this bearing there is a yoke arm 28 having two branches 29 and 30. For 60 the sake of lightness of construction these are ribbed. A brace designated by the assembly numeral 31 has a clamping end 32 which is secured tightly around the extension arm 25 at the end of the bearings 27 and this brace has a pair of diverging straps 33 which attach to the flange or outer portion of the lamp housing, as indicated at 34. (Note Fig. 3).

The general mounting for the arm assembly 26 is as follows, having reference particularly to 70 Fig. 5:

A pair of journal bases 35 and 36 are secured to the base plate 14 and each of these has a journal section 37 with bushings 38 therein. Rotatable in these bushings there is a main tubular 75 rotatable shaft designated by the assembly nu-

meral 39. This has a tubular sleeve 40, a plug 41 fitted snugly in one end, a cover plate 42 secured to the plug by means of the screw 43; a hub 44 is fitted on the outside of the sleeve 40 and connected to this sleeve and the plug 41 by means of the pin 45. A radially extending segmental flange 46 extends outwardly from the hub and has a segmental rim 47. A segmental worm wheel 48 is secured to the hub. This wheel has a segmental groove 49 and is attached to the flange 46 by means of pins 49'. The worm wheel has worm teeth 50. (Note Figs. 5 and 7).

The mounting for the opposite end of the main oscillating shaft and also the structure which houses the reciprocating rod for tilting and inclining the lamp is as follows, having reference particularly to Figs. 5 and 6. Spaced from the journal bases 35 and 36 there is a journal base 51 secured to the base plate 14. This has a journal 52 with a bushing 53 therein and rotatably mounted in the bushing there is a sleeve 54 forming, in effect, a part of the main rotating shaft 39. To the sleeve 40 the hub 55 of the branch arm 30 of the yoke arm 28 is secured, as by means of a key 56. The branch arm 29 has a similar hub 57 secured to the end of the sleeve 54 by a key 58.

The mechanism for rotating the main tubular shaft 39 to project the lamp from its housing or to retract it into such housing is as follows, having reference particularly to Figs. 1, 5 and 7:

A worm gear housing designated by the assembly numeral 59 extends upwardly from the journals 37 and in this there is mounted a worm shaft 60, this having anti-friction ball bearings 61 of any suitable character. The gear housing is made in two sections secured by bolts 62. A worm 63 is secured in any suitable manner on the worm shaft 60, this being illustrated as by a collar 64 and pin construction 65. Secured to the outer projecting end of the worm shaft there is a driving drum or sheave 66, this being illustrated as keyed to the worm shaft 60 at 67 and having grooves 68 for the operating cable 69, which cable leads to a suitable operating mechanism, not illustrated, under the control of the pilot. A partial protective housing 70 forms an integral part of the gear housing 59 and encloses part of the sheave 66.

By this construction when the sheave 66 is rotated by movement of the cable 69, which cable is preferably secured to the sheave in any suitable manner, the worm shaft 60 is rotated, and on account of meshing with the teeth 50 of the segmental worm gear 48 this gear is oscillated and transmits motion through the hub 44 to the sleeve 40 of the main oscillating tubular shaft 39, the plug 41, as above mentioned, forming a stiffening and bracing element. The torque transmitted to the sleeve 40 is transferred by the hub 55 to the arm 30 of the yoke arm 28. The sleeve 54 is not driven but acts as an idle support for the branch arm 29 of the yoke 28, this sleeve 54, as above mentioned, rotating in the bushing 53. On account of the longitudinal bearing hub 27 being formed integral with the yoke arm 28 the oscillation of the yoke arm oscillates the bearing, and, hence, the extension arm 25, and thereby swings the lamp housing in a plane at right angles to the axis of the tubular shaft 39 to project or extend the lamp outside of the structure in which it is housed or to retract it within such structure.

For instance: if the lamp is housed in the lower surface of the wing and such surface presumed to be substantially horizontal when the airplane is flying in a horizontal plane, the lamp in its pro-

jecting and retracting movement will swing in a vertical plane or if the lamp is housed in the sides of the fuselage; for instance, the nose of the fuselage; with the tubular shaft 39 vertical the oscillating movement of the extension arm 25 in projecting and retracting the lamp housing will be in a horizontal plane.

The mechanism for tilting or inclining the lamp by rotating the extension arm on its axis is as follows, having reference particularly to Figs. 1, 2, 3, 4, 5, and 6:

As above mentioned, the journal base 51 has a journal 52 at one side with a bushing and at the opposite side there is a journal base 75 which is constructed in the worm housing 76. A bushing 77 is mounted in the journal 75, such bushing having a flange 78. A sleeve bushing 79 fits inside of the sleeve section 54 and a second sleeve bushing 80 fits inside the sleeve 40. A reciprocating rod 81 has an enlarged end 82 slidable in the bushing sleeve 79 and has an enlarged collar 83 secured to its opposite end by a pin 84 and slidable in the sleeve bushing 80. A screw 85 is formed on the enlargement 82 and is also slidable in the sleeve 79 and in the sleeve 77, the sleeve 77 having a groove 86 engaged by the pin 87 through the enlarged end to prevent rotation of the rod 81. A drum or sheave 88 has a threaded wearing internal worm 89 engaging the threads 85. This sheave 88 has a helical groove 90 around which is wrapped a control cable 91. A semi-circular protective cover 92 forms a partial housing for the sheave and the cable.

The means for transmitting motion from the reciprocating rod 81 to the extension arm 25 is as follows: (Note particularly Figs. 1, 2, 3, and 5.)

An oscillating arm 93 has a hub section 94 secured to the end of the extension arm 25 by a pin 95 or the like. This hub, preferably, abuts closely one end of the bearing hub 27. The arm 93 has a lateral extension 96 with a hub 97 having a perforation 98. This perforation is, preferably, oval and allows free passage of the rod 81 there-through and in oscillation of the arm 93 the rod 81 cannot contact with either the upper or lower surfaces of the perforation. The opposite surfaces of the hub 97 are spherically curved, as indicated at 99, forming parts of a sphere of large radius. There are two coiled springs 100 coiled on the rod 81 and one spring bears on the enlargement 82 and the hub 97 and the other spring bears on the enlarged collar 83 and the hub 97.

By the above described construction when the lamp is normally in its housed position and it is not intended to be tilted by the rotation of the arm 25 the hub 97 on the arm 93 occupies a mid-position between the arms of the yoke bracket 28. However, after the lamp has been moved out of its housed position a longitudinal movement of the rod 81 in either direction causes a rotational movement of the arm 93. This arm is held resiliently in position by the two springs 100. These springs are of equal strength so that normally the hub 97 is midway between the enlargements 82 and 83 of the rod 81. A swinging movement of the arm 93 through the medium of the hub 94 and the pin 95 rotates the extension arm 25 on its axis and thus tilts or inclines the lamp as indicated by the dotted lines in Fig. 4.

As above mentioned the brace 31 is clamped to the extension arm 25 and also to the flange of the lamp and aids in holding the lamp in a steady position. The springs 100 are sufficiently stiff so

that when a lamp is tilted or inclined the wind pressure does not cause a vibration of the lamp.

By this construction if the lamp is housed in the bottom of the wing and the arm 25 is swung in a vertical plane the beam of light may be tilted or inclined to the right or the left of this vertical plane. Or if the lamp is housed in the fuselage and the arm 25 swings outwardly in a horizontal plane a beam of light may be tilted either upwardly or downwardly from the plane of movement of the arm 25.

The mechanism and construction for bringing the lamp into its neutral position for housing, even if it is tilted, is as follows:

The operator or pilot in handling the lamp may not wish to return the lamp by moving the rod 81 to a neutral position but he may want to have this left so that if the lamp is projected by swinging the arm 25 in a plane the lamp when projected from the housed position will have the beam of light tilted or inclined. But it is necessary for the lamp to be centered in order that it may house snugly with the flange 17 of the lamp in contact with the ring 13 on the airplane structure. To obtain this automatic movement a guide track structure 101 is used. This has a base 102 secured to the plate 14 and has a pair of parallel spaced rails 103, each of which has a diverging end 104 (note Figs. 1, 2, 3 and 5). The arm 93 is provided with a slight extension 105 and this has a beveled surface 106 against which is placed a guide wheel 107 mounted on a stud 108 secured in the extension and at right angles to the inclined face 106. Therefore, when the lamp is shifted from its extended position of Fig. 3 to the housed position of Fig. 2 and the arm 93 is inclined out of its neutral position the wheel 107 will engage first either one of the flared rail ends 104 and guide the wheel and thus the arm 93 into its neutral or center position when the wheel will fit between the two parallel rail sections 103. When this action occurs and the enlargements 82 and 83 of the rod 81 are not centrally positioned one of the springs 100 will become compressed and the other extended. However, this does not prevent the proper housing of the lamp which is now centered so that the flange 17 of the lamp engages the ring 13 on the airplane structure.

As above mentioned, cables 69 and 91 may lead to a convenient control mechanism and thus the pilot or operator of the lamps can swing a lamp outwardly from its housed position through any desired arcuate movement and then tilt or incline the lamp in order to project a beam of light to one side or the other of the plane of movement of the arm 25. The operator need not return the lamp to its neutral position for housing but he merely has to retract the arm 25 by rotating the tubular shaft 39 to bring the lamp again into its housed position.

In Fig. 8 I have shown in diagram part of an airplane and in the wings the lamps are shown dotted to represent these as on the lower surface. Other lamps are illustrated as being in the nose of the wing, one on each side.

Various changes may be made in the principles of my invention without departing from the spirit thereof, as set forth in the description, drawings and claims.

I claim:

1. In a retractable landing light, a rotatable shaft having an arm with an inner and outer section at substantially right angles, the inner section being secured to the shaft, a lamp secured to the outer section whereby on rotation of the

- shaft the arm swings in a plane and the lamp may be moved in arcuate movement from a housed to an extended position, the outer section of the arm being rotatable on its axis and means to rotate said outer section to tilt or incline the lamp in reference to the plane of its arcuate swinging movement.
2. In a retractable landing light, as claimed in claim 1, the means to rotate the arm on its axis having a resilient mounting and means cooperative with the resilient mounting to return the arm to its neutral position on retraction by a reTRACTING rotation of the said shaft.
3. In a retractable landing light, comprising in combination, a hollow shaft, an angularly shaped arm connected thereto, an outer section of said arm being rotatable on its axis, a lamp secured to the outer end of the outer section, means to rotate said shaft to swing the lamp in an arcuate plane, a rod, means to reciprocate said rod in said hollow shaft and an operating connection from the said rod to the said outer section of the arm to rotate the arm on its axis to incline or tilt the lamp in reference to its plane of arcuate movement.
4. In a retractable landing light, as claimed in claim 3, the connection between the rod and the outer rotational arm section comprising an oscillating arm secured to the arm section, a resilient connection between the rod and the said oscillating arm and a guide structure to center the oscillating arm on retraction of the lamp to its lamp housing independent of movement of the reciprocating rod to a neutral position.
5. In a retractable landing light, comprising in combination, a hollow rotatable shaft formed in axially spaced parts, a yoke bracket arm having two branches, each connected to said shaft, said yoke arm having a hub, an extension arm rotatably mounted in said hub having a lamp secured to the outer end of the extension arm, and means to rotate one part of the rotatable shaft and thereby swing the extension arm and the lamp in an arcuate path.
6. In a retractable landing light, as claimed in claim 5, a rod slidably mounted in the hollow shaft and having a bearing in each section of the shaft, an oscillating arm connected to the extension arm, an interengaging means between the reciprocating rod and the oscillating arm to oscillate said arm on reciprocation of the rod and thus tilt or incline the lamp in reference to its plane of arcuate movement.
7. In a retractable landing light, as claimed in claim 5, a rod slidably mounted in the hollow shaft and having a bearing in each section of the shaft, an oscillating arm connected to the extension arm, an interengaging means between the reciprocating rod and the oscillating arm to oscillate said arm on reciprocation of the rod and thus tilt or incline the lamp in reference to its plane of arcuate movement, the interconnection between the oscillating arm and the reciprocating rod comprising springs connected to the rod and engaging a hub on the oscillating arm and a centering means comprising a guide track structure and means on the oscillating arm to engage said structure on swinging of the lamp in an arcuate movement from an extended to a housed position.

LESTER F. LEMM. 35
